UNITED STATES PATENT OFFICE.

ROBERT A. HORNING, OF BROOKVILLE, ASSIGNOR OF ONE-HALF TO GEORGE D. AND JOHN L. REYNOLDS, OF LANARK, ILLINOIS.

LAND-ROLLER.

SPECIFICATION forming part of Letters Patent No. 266,155, dated October 17, 1882.

Application filed March 30, 1882. (No model.)

To all whom it may concern:

Be it known that I, ROBERT ALLEN HORN-
ING, of Brookville, in the county of Ogle and
State of Illinois, have invented a new and use-
ful Improvement in Land-Rollers, of which the
following is a full, clear, and exact description.

My invention consists in a novel construc-
tion and arrangement and combination of two
cylinders, one working diagonally in advance
10 of the other, a frame-work to which said cylin-
ders are connected, and certain details of con-
struction and arrangement of the hubs, axles,
braces, and an adjustable seat, as hereinafter
more particularly described.

Reference is to be had to the accompanying
drawings, forming part of this specification, in
which similar letters of reference indicate cor-
responding parts in all the figures.

Figure 1 is a side view of an apparatus em-
bodying my improvements. Fig. 2 is a back
view, partly in section. Fig. 3 is a plan view.

A represents a cylinder composed of staves
having their ends beveled, and fitting into a
head consisting of a band, B, having its outer
25 edge turned outward and backward into a
flange, b, the outer surface of which is rounded
and the inner surface forms a V-shaped per-
ipheral groove. Each cylinder has two of these
heads, the grooves of which embrace the be-
veled ends of the staves, and thus support them
30 in every direction, the bands being bolted at
intervals to several of the staves. From four
or more equidistant points on the interior of
the cylinder four radial braces, C, extend to-
ward the center, where they are attached to a
35 hub, D, provided with radial wings d, which
are bolted to said braces C. In the hub D
works an axle, E, the outer end of which is
provided with a pin, e, and washer e², and the
40 inner end with a transverse pivot, f, which is
engaged by the outer ends of two clamping
plates, g, having their inner ends bolted to one
end of a horizontal beam, H, carried by the
lower end of a hanger, J, the upper end of
45 which is attached to a horizontal rail, K. Two
of these rails are arranged side by side, and
connected at front and rear by cross-beams, to
the forward one of which is attached the pole
or tongue L, provided with a bolt, l, for con-

necting a whiffletree. The two cylinders A 50
are arranged with one diagonally in advance
of the other, with one of the hangers J depend-
ing from the outer side of one of the rails K
and the other hanger depending from the outer
side of the other rail. The rails K, hangers 55
J, beams H, and axles E are connected and
braced by a brace consisting of an iron bar, R,
bent in the shape of the letter W, with one
end bolted to one rail, the other end bolted to
the other rail, and the intermediate upper an- 60
gle bolted to the tongue L or other suitable
part of the frame, at about the center thereof,
while the lower angles are formed into bear-
ings, which engage with the outer ends of the
axles E. The seat M is carried by the upper 65
end of a curved elastic bar, P, the lower end
of which passes under a foot-board, Q, and
rests upon the top of the tongue L or the frame
formed by the rails and their connecting cross-
bars. In the bar P is a longitudinal slot, p, 70
through which bolts q pass into the tongue or
frame, by which means the seat is held in
place and provision is made for adjusting it
forward or backward in order to accommodate
it to the weight of the driver. 75

The advantages of my invention are: The
rollers being diagonally one in advance of the
other, provision is made for allowing their in-
ner ends to pass beyond a line drawn through
the longitudinal center of the frame, and thus 80
avoid the break in the work which would oc-
cur if the two rollers were in the same axial
line. By means of the rounded ends the ma-
chine is enabled to turn more easily, and by
means of the pivots f each roller is enabled to 85
automatically adjust itself to inequalities of the
ground independently of the other.

Having thus fully described my invention, I
claim as new and desire to secure by Letters
Patent—

1. A roller consisting of end-beveled staves,
two bands, B B, turned backward to form a
flange, b, rounded on the outside and V-shaped
on the inside, radial braces, and a hub having
radial wings bolted to said braces, as shown and 95
described.

2. In a land-roller, the combination of the
cylinders A, the radial braces C, and the hubs

D, provided with the radial wings *d*, substantially as and for the purposes herein described.

3. In a land-roller, the combination, with the hub D, beam H, and clamping plates *g*, of the 5 axles E, provided with the horizontal transverse pivots *f*, substantially as and for the purpose herein described.

4. The combination, with the axles, rails, and

tongue, of the **W**-braces R, having a bearing at each angle, a connection with one of the rails 10 at each free end, and attached in the middle to the tongue, as shown and described.

ROBERT ALLEN HORNING.
